INVENTOR:
GEORGE R. ADAMS
BY
F. A. Davis
ATTORNEY.

UNITED STATES PATENT OFFICE.

GEORGE R. ADAMS, OF LOS ANGELES, CALIFORNIA.

LINGERIE CLASP.

Application filed February 15, 1926. Serial No. 88,263.

This invention relates to a novel and improved form of lingerie clasp. Certain styles of ladies' lingerie employ straps which extend over the shoulders for holding the bodice thereof in place. There is a tendency for these straps to slip from the shoulders and onto the arms. To prevent this, it is ordinary to use what is called a "lingerie clasp" which engages each strap and which also is attached to the outer garment of the wearer. It is highly desirable to have a lingerie clasp which will release the lingerie straps when the outer garment is removed so that the straps or the outer garment will not be torn or otherwise damaged.

It is an object of my invention to provide a lingerie clasp which will engage a lingerie strap and hold it in place but will release it if sufficient pull is exerted thereon.

It is another object of this invention to provide a lingerie clasp of the character mentioned which is very simple and neat in design and may be worn without being noticed.

Other objects and particular advantages of my invention will be made manifest hereinafter.

Referring to the drawing which is for illustrative purposes only,

Fig. 1 is a fragmentary view illustrating the utility of the invention.

Fig. 2 is a section taken on the line 2—2 of Fig. 1.

Fig. 3 is an enlarged perspective view of the invention.

Fig. 4 is a horizontal section taken on the line 4—4 of Fig. 3.

Fig. 5 is a section similar to Fig. 4 but showing the clasp bar of the invention in closed position.

Fig. 6 is a section taken on the line 6—6 of Fig. 4.

Referring to Figs. 3 to 6 inclusive, my invention has a body 11. The body 11 consists of an elongated web portion 12, from the opposite sides of which there project edge walls 13, these edge walls 13 extending parallel and in the same direction from the web 12. At one end of the body 11 there is formed a pair of ears 15, these ears being enlarged parts of the side walls 13. These

ears 15 are disposed directly opposite from one another, as best shown in Figs. 3 and 6. Trunnions 16 extend into openings formed in the ears 15 for pivotally securing a clasp bar 17 to the body 11. The clasp bar 17 is adapted to swing between a closed position as shown in Fig. 5 and an unclosed position as shown in Figs. 3 and 4. When the clasp bar 17 is in closed position it extends substantially parallel to the web 12 of the body 11, and when it is in open position it extends substantially at right angles to the web of the body 11. The clasp bar 17 is bent to extend laterally near the pivoted end thereof as indicated at 19, so as to provide a main offset portion 20. The extreme end of the clasp bar 17 is bent inwardly as indicated at 21. Therefore, when the clasp bar 17 is in closed position, as illustrated in Fig. 5, there is a space provided between the offset portion 20 of the clasp bar 17 and the body 11.

The end of the body 11 opposite from the ears 15 is provided with a pair of flanges 23 which are pressed against the front face of the web 12. The flanges 23 are provided for the purpose of attaching a spring 24 to the body 11. The free end of the spring 24 extends through an elongated opening 25 formed in the clasp bar 17 at the laterally bent part 19 thereof. An inwardly extending hook 27 is formed at the extreme end of the spring 24. The tendency of the spring 24 is to lie flat against the front face of the web 12. Since it is deflected from this position and extended through the opening 25, there is always a pressure against the wall of the opening 25 adjacent to the body 11.

When the clasp bar 17 is in closed position, the spring 24 rests in the position shown in Fig. 5, and exerts a resilient pressure on the pivoted end of the clasp bar 17 and resiliently holds it in this closed position. When the clasp bar 17 is moved into open position it may be swung until the hook 27 engages the outer face thereof, at which time it cannot be swung any farther. The resilient pressure placed on the clasp bar 17 at this time is in a direction indicated by the arrow 29 of Fig. 4, and the clasp bar 17 is therefore retained in open position.

The web 12 is provided with an opening 31 below the flanges 23. Extending through the opening 31 is a continuation of the spring 24 which comprises a pin 32 of the 5 invention. The pin 32 may be held in pinning position by a pocket 33 which is illustrated clearly in Fig. 6. The pocket 33 is formed from an extending tip 34 of the web portion 12 which is bent back parallel to 10 the web 12 and one edge 35 bent down against the web 12 as shown in Fig. 6. This provides the pocket 33 in which the point of the pin 32 may rest. The metal in the tip 34 is also bent outwardly to form a retaining groove 36 in the outer surface of 15 the pocket 33 in which the pin 32 will tend to be retained by its resilient outward pressure. From the opposite end of the web 12 there extends a short tip of metal 38 which 20 is bent up to cover the ends of the flanges 23 and to overlap the bent end 21 of the clasp bar 17 when it is in closed position as shown in Fig. 5.

In using the lingerie pin of this invention 25 the pin 32 is extended through an outer garment 40, as illustrated in Figs. 1 and 2, and the free end thereof is then hooked in the pocket 33. The clasp bar 17 may be moved into open position and a lingerie strap, as 30 indicated at 41, may be extended in contact with the front side or the lower side of the body 11. The clasp bar 17 is then removed from open position into closed position so that it surrounds the lower part of the lingerie strap 41. The bent end 21 of the clasp bar 17 may engage the flanges 23, as shown. 35 By providing the clasp bar 17 with an offset portion 20 a channel is provided to receive the lingerie strap 41. If the wearer forgets 40 to unpin the lingerie clasp, which is often done, there will be no damage when the outer garment or dress 40 is removed. The clasp bar 17 is merely swung into open position against the action of the spring 24, and the 45 lingerie strap 41 is released.

From the foregoing description it will be readily perceived that the lingerie clasp of my invention entirely prevents any damage being done to the user's clothing. The clasp 50 bar and spring arrangement 17 and 24 of the invention is extremely simple and effective. The resilient pressure of the springs 24 on the clasp bar 17 does not have to be very much to retain the lingerie strap 41 on the shoulders; therefore, a very light pull will move the clasp bar 17 into open position to release the lingerie strap 41. However, while the outer clothing 40 rests relatively close to the body the clasp bar 17 will remain in closed position, and the overlapping 55 relation of the clasp bar's bent end 21 and the bent body tip 38 will effectually retain the lingerie strap 41 against removal from the clasp.

I claim as my invention:

1. A lingerie clasp comprising: a body having an elongated web portion having ears extending from said elongated web portion near one end thereof; a clasp bar pivotally attached to said ears, said clasp bar being swingable from a closed position substantially parallel to said body into an open position; a spring secured to the opposite end of said elongated web portion from said ears, said spring extending through an opening 70 in said clasp bar, said spring engaging said clasp bar in such a manner as to resiliently hold said clasp bar in closed position when said clasp bar is in closed position, and to resiliently hold said clasp bar in open position 75 when said clasp bar is in open position; and a pin secured to said elongated web portion 80 on the opposite side from said clasp bar.

2. A lingerie clasp comprising: a body consisting of a flat elongated web portion having ears extending from the sides of said flat elongated portion near one end thereof; a clasp bar pivotally attached to said ears, said clasp bar being swingable from a closed 85 position substantially parallel to said body into an open position; a spring bent centrally to form a pointed pin portion and a clasp actuating portion; means for securing said spring near the bend therein to said body at the opposite end from said ears so 90 that said clasp actuating portion extends from said securing means and engages said clasp bar near the pivotal axis thereof, and so that the pin portion of said spring extends from said securing means along the reverse side of the body to the opposite end thereof; and a pocket formed upon said body 95 to receive the pointed end of said pin portion.

3. A combination as set forth in claim 1 in which the tip of said clasp bar is bent toward said body; and a tip formed on an end of said body is bent toward said clasp bar so that the two aforesaid tips will overlap when said clasp bar is in closed position.

4. A lingerie clasp comprising: a body consisting of a flat elongated web portion having ears extending from the sides of said flat elongated portion near one end thereof; a clasp bar pivotally attached to said ears, 110 said clasp bar being swingable from a closed position substantially parallel to said body into an open position; a spring bent centrally to form a pointed pin portion and a clasp actuating portion; a securing flange 115 formed upon said body at the opposite end thereof from said ears opposite an aperture provided in said body, said flange being bent down upon said spring, when the bend thereof is positioned in said aperture, and thereby securing said spring to said body so that said clasp actuating portion extends from said securing flange and engages said

clasp bar near the pivotal axis thereof, and so that the pin portion of said spring extends from said securing flange along the reverse side of the body to the opposite end thereof; and a pocket formed upon said body to receive the pointed end of said pin portion.

5. A lingerie clasp comprising: a body consisting of a flat elongated web portion having ears extending from the sides of said flat elongated portion near one end thereof; a clasp bar pivotally attached to said ears, said clasp bar being swingable from a closed position substantially parallel to said body into an open position; a spring bent centrally to form a pointed pin portion and a clasp actuating portion; means for securing said spring near the bend therein to said body at the opposite end from said ears so that said clasp actuating portion extends from said securing means and engages said clasp bar near the pivotal axis thereof, and so that the pin portion of said spring extends from said securing means along the reverse side of the body to the opposite end thereof; a pocket formed upon said body to receive the pointed end of said pin portion; a tip bent from the end of said clasp bar toward said body; and a tip formed on an end of said body and bent toward said clasp bar so that the two aforesaid tips will overlap when said clasp bar is in closed position.

6. A lingerie clasp comprising: a body consisting of a flat elongated web portion having ears extending from the sides of said flat elongated portion near one end thereof; a clasp bar pivotally attached to said ears, said clasp bar being swingable from a closed position substantially parallel to said body into an open position; a spring bent centrally to form a pointed pin portion and a clasp actuating portion; a securing flange formed upon said body at the opposite end thereof from said ears opposite an aperture provided in said body, said flange being bent down upon said spring, when the bend thereof is positioned in said aperture, and thereby securing said spring to said body so that said clasp actuating portion extends from said securing flange and engages said clasp bar near the pivotal axis thereof, and so that the pin portion of said spring extends from said securing flange along the reverse side of the body to the opposite end thereof; a pocket formed upon said body to receive the pointed end of said pin portion; a tip bent from the end of said clasp bar toward said body; and a tip formed on an end of said body and bent toward said clasp bar so that the two aforesaid tips will overlap when said clasp bar is in closed position.

7. A lingerie clasp comprising: a body consisting of a flat elongated web portion having ears extending from the sides of said

flat elongated portion near one end thereof; a clasp bar pivotally attached to said ears, said clasp bar being swingable from a closed position substantially parallel to said body into an open position; a spring for resiliently holding said clasp bar in closed position and in open position, said spring being secured to the opposite end of said body from said ears, said spring extending through an opening in said clasp bar and tending to close said clasp bar, said spring having a stop formed upon its end which limits the open position of said clasp bar; and a pin secured to said body on the side opposite from said spring.

8. A lingerie clasp comprising: a body consisting of a flat elongated web portion having ears extending from the sides of said flat elongated portion near one end thereof; a clasp bar pivotally attached to said ears, said clasp bar being swingable from a closed position substantially parallel to said body into an open position, said bar having an outwardly offset portion which provides a space between said body and said clasp bar when the latter is in closed position; a spring for resiliently holding said clasp bar in closed position and in open position, said spring being secured to the opposite end of said body from said ears, said spring extending through an opening in said clasp bar and tending to close said clasp bar; and a pin secured to said body on the side opposite from said spring.

9. A lingerie clasp comprising: a body consisting of a flat elongated web portion having ears extending from the sides of said flat elongated portion near one end thereof; a clasp bar pivotally attached to said ears, said clasp bar being swingable from a closed position substantially parallel to said body into an open position, said bar having an outwardly offset portion which provides a space between said body and said clasp bar when the latter is in closed position; a spring bent centrally to form a pointed pin portion and a clasp actuating portion; means for securing said spring near the bend therein to said body at the opposite end from said ears so that said clasp actuating portion extends from said securing means and engages said clasp bar near the pivotal axis thereof, and so that the pin portion of said spring extends from said securing means along the reverse side of the body to the opposite end thereof; and a pocket formed upon said body to receive the pointed end of said pin portion.

10. A lingerie clasp comprising: a body consisting of a flat elongated web portion having ears extending from the sides of said flat elongated portion near one end thereof; a clasp bar pivotally attached to said ears, said clasp bar being swingable from a closed position substantially parallel to said body

into an open position, said bar having an outwardly offset portion which provides a space between said body and said clasp bar when the latter is in closed position; a spring bent centrally to form a pointed pin portion and a clasp actuating portion; a securing flange formed upon said body at the opposite end thereof from said ears opposite an aperture provided in said body, said flange being bent down upon said spring, when the bend thereof is positioned in said aperture, and thereby securing said spring to said body so that said clasp actuating portion extends from said securing flange and engages said clasp bar near the pivotal axis thereof, and so that the pin portion of said spring extends from said securing flange along the reverse side of the body to the opposite end thereof; and a pocket formed upon said body to receive the pointed end of said pin portion.

11. A lingerie clasp comprising: a body consisting of a flat elongated web portion having ears extending from the sides of said flat elongated portion near one end thereof; a clasp bar pivotally attached to said ears, said clasp bar being swingable from a closed position substantially parallel to said body into an open position, said bar having an outwardly offset portion which provides a space between said body and said clasp bar when the latter is in closed position; a spring bent centrally to form a pointed pin portion and a clasp actuating portion; means for securing said spring near the bend therein to said body at the opposite end from said ears so that said clasp actuating portion extends from said securing means and engages said clasp bar near the pivotal axis thereof, and so that the pin portion of said spring extends from said securing means along the reverse side of the body to the opposite end thereof; a pocket formed upon said body to receive the pointed end of said pin portion; a tip bent from the end of said clasp bar toward said body; and a tip formed on an end of said body and bent toward said clasp bar so that the two aforesaid tips will overlap when said clasp bar is in closed position.

12. A lingerie clasp comprising: a body consisting of a flat elongated web portion having ears extending from the sides of said flat elongated portion near one end thereof; a clasp bar pivotally attached to said ears, said clasp bar being swingable from a closed position substantially parallel to said body into an open position, said bar having an outwardly offset portion which provides a space between said body and said clasp bar when the latter is in closed position; a spring bent centrally to form a pointed pin portion and a clasp actuating portion; a securing flange formed upon said body at the opposite end thereof from said ears opposite an aperture provided in said body, said

flange being bent down upon said spring, when the bend thereof is positioned in said aperture, and thereby securing said spring to said body so that said clasp actuating portion extends from said securing flange and 70 engages said clasp bar near the pivotal axis thereof, and so that the pin portion of said spring extends from said securing flange along the reverse side of the body to the opposite end thereof; a pocket formed upon said body to receive the pointed end of 75 said pin portion; a tip bent from the end of said clasp bar toward said body; and a tip formed on an end of said body and bent toward said clasp bar so that the two aforesaid tips will overlap when said clasp bar is in closed position.

13. A lingerie clasp comprising: a body consisting of a flat elongated web portion having ears extending from the sides of said flat elongated portion near one end thereof; a clasp bar pivotally attached to said ears, said clasp bar being swingable from a closed position substantially parallel to said body into an open position, said bar having an 80 outwardly offset portion which provides a space between said body and said clasp bar when the latter is in closed position; a spring for resiliently holding said clasp bar in closed position and in open position, said spring being secured to the opposite end of said body from said ears, said spring extending through an opening in said clasp bar and tending to close said clasp bar, said spring having a stop formed upon its end which 85 limits the open position of said clasp bar; and a pin secured to said body on the side opposite from said spring.

14. A lingerie comprising: an elongated body; a clasp bar pivoted to said body near one end thereof, said clasp bar having an open and a closed position; a spring attached to said body, said spring engaging said clasp bar in such a manner as to resiliently hold said clasp bar in open position and also in closed position; and a pin secured to said body on the side opposite from said clasp bar.

15. A lingerie clasp comprising: an elongated body; a clasp bar pivoted to said body near one end thereof, said clasp bar having a closed position in which it lies substantially parallel to said body and an open position in which it extends substantially at right angles to said body; a spring attached to said body, said spring engaging said clasp bar in such a manner as to resiliently hold said clasp bar in open position and also in closed position; and a pin secured to said body on the side opposite from said clasp bar.

16. A lingerie clasp comprising: an elongated body; a clasp bar pivoted to said body near one end thereof, said clasp bar having a closed position in which it lies

substantially parallel to said body and an open position in which it extends substantially at right angles to said body; a spring attached to said body, said spring engaging

5 said clasp bar in such a manner as to resiliently hold said clasp bar in open position and also in closed position, said spring extending along said body, the free end there-

of engaging said clasp bar and exerting a pressure thereon towards said body; and a 10 pin secured to said body on the side opposite from said clasp bar.

In testimony whereof, I have hereunto set my hand at Los Angeles, California, this 9th day of February, 1926.

GEORGE R. ADAMS.
